UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

REINFORCED-METAL STRUCTURE FOR RAILWAY CARS.

Application filed February 11, 1926. Serial No. 87,654.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

10 My invention relates to the construction of railway cars and more particularly to metal end structures or walls for railway cars made of one or more metallic plates or panels formed with integral reenforcing, 15 stiffening and bracing embossments or corrugations. However, this device may be incorporated in the construction of car side walls, floors, roofs or doors used in connection with railway cars of various types.

20 It is well known that the end walls of railway box cars are more likely to be broken or otherwise injured than the side walls. This is due to the inertia thrusts and pressures caused by the shifting of the cargoes 25 when the train starts or stops. These thrusts may be local, tending to distort the end in some particular spot, as, for example, when a piece of piping or lumber shifts lengthwise imparting a blow against the end wall of the 30 car; or there may be a general tendency to break out the end wall as a whole or tear it away from the framing. For the purpose, therefore, of greater strength and durability, car ends have been constructed of metal 35 plates corrugated or formed with ribs to impart the desired strength, rigidity and resiliency.

One of the principal objects of my invention is to provide a corrugated metallic end structure for railway cars in which the corrugations have a configuration and arrangement that impart to the structure a maximum capacity for resisting cargo thrusts, both local and general, static or quiescent, 45 and with sufficient resiliency to prevent permanent distortion due to the thrusts of the loads, with a minimum weight of metal. It is important that structures of this sort should be as light as is possible, consistent 50 with strength and durability, both for reasons of economy in manufacturing cost and also to keep the weight of the car at a minimum.

The retaining walls of railway cars are 55 lined to retain the cargo within the car, be-

cause a riveted joint between two flat steel surfaces will not retain such fine lading as grain, sand, etc. Steel frame (and even wooden cars) are lined with wood which absorbs moisture and retards sweating. If 60 grain were allowed to contact with a steel wall the consequent condensation of the moisture in the atmosphere would cause mildew, and in such ladings as cement and flour (even though sacked) such moisture 65 would cause considerable damage. A wooden lining between the steel wall and the lading practically eliminates such condensation. A wooden lining also furnishes excellent means for blocking bulky and package lading in 70 place.

Any lining necessarily increases the thickness of the wall and in an end wall this means that the inside length of the car is reduced or the train length of the car is increased, either of which is objectionable. It is desirable, therefore, to provide as thin a lining as possible consistent with requirements and to support the lining by means which occupy the minimum possible horizontal space.

While I have shown the corrugations positioned horizontally, this is immaterial to the essential features of the invention. In the preferred form the corrugations terminate within the opposite edges of the plate. The wall may be made of one or more plates as desired.

In the form illustrated, the metallic plates extend from side to side of the car and are attached thereto and to the end sill and end plate in any convenient manner and are secured together along horizontal lines, thus forming the end wall of the car.

In the drawings:

Fig. 1 shows an end elevation of a railway car with my device applied thereon.

Fig. 2 is a section on line 2—2 of Fig. 1.

Fig. 3 is an enlarged cross section on line 3—3 of Fig. 1.

Fig. 4 is an elevation of Fig. 3.

Fig. 5 is a section on line 5—5 of Fig. 4.

Fig. 6 shows a modified form.

The metallic wall or panel is made of one or more metallic plates (1—2—3) secured together and reenforced and stiffened by one or more integral embossments 4 which preferably terminate within the opposite edges of the metallic plates. These embossed reinforcements comprise a central portion 5 and 105

longer portions 6 on each side thereof with their extremities separated from the central portion and with their medial parts joined to the middle of the central portion. To accomplish this result the central portion may be made straight and the longer secondary portions deflected and vice versa, or they may all be made straight and parallel, as shown in Fig. 6.

10 The central portion of the embossed reenforcement is preferably straight and of constant depth and constant width for the major portion of its length, and may be deeper or shallower or may be wider or narrower than the unitary side portions of the embossed reenforcement.

13 The attaching pieces, which are preferably made of wood, are fitted into and secured to the central portion of the embossment, 20 which is preferably made straight, so that the nailing strip will be simple to make and to apply. Lining boards are positioned perpendicularly to the attaching pieces and nailed or otherwise secured thereto. The attaching pieces are the same depth as the portion of the embossment into which they are secured, the lining boards, therefore, not only bear against the attaching piece but also against the plate between the central portion 30 and the other portion of the embossment.

When the reinforced plate is attached to a frame member of the car, or car part, the longer side portions preferably overlap the frame member and rivets; bolts or other attaching means are positioned between the extremities of the longer portions, and preferably in alignment with the central portion. In such an arrangement, the beam stresses of the embossment are transmitted directly 35 by the rivets to the frame member; furthermore, the arrangement restrains the embossment as a beam against deflection, thereby increasing its strength.

I claim:

45 1. In a railway car part made of a metallic plate having an embossed reenforcement formed therein comprising a central portion, and a longer portion on each side of said central portion and partially parallel therewith and having their extremities separated therefrom and their middles joined thereto.

55 2. In a railway car part made of a metallic plate having an embossed reenforcement formed therein terminating within the opposite edges of the plate comprising a central portion, and a longer portion on each side of said central portion and partially parallel therewith and having their extremities separated therefrom and their middles joined thereto.

60 3. In a railway car part made of a metallic plate having an embossed reenforcement formed therein comprising a central portion, and a shallower, longer portion on each side of said central portion and partially parallel

therewith and having their extremities separated therefrom and their middles joined thereto.

4. In a railway car part made of a metallic plate having an embossed reenforcement 70 formed therein terminating within the opposite edges of the plate comprising a central portion, and a shallower, longer portion on each side of said central portion and partially parallel therewith and having their 75 extremities separated therefrom and their middles joined thereto.

5. In a railway car part made of a metallic plate having an embossed reenforcement 80 formed therein comprising a central portion, and a shallower, narrower, longer portion on each side of said central portion and partially parallel therewith and having their 85 extremities separated therefrom and their middles joined thereto.

6. In a railway car part made of a metallic plate having an embossed reenforcement formed therein comprising a central portion of constant depth, the major portion of its length, and a longer portion on each side 90 of said central portion and partially parallel therewith and having their extremities separated therefrom and their middles joined thereto.

7. In a railway car part made of a metallic plate having an embossed reenforcement 95 formed therein comprising a central portion of constant depth and constant width the major portion of its length, and a longer portion on each side of said central portion 100 and partially parallel therewith and having their extremities separated therefrom and their middles joined thereto.

8. In a railway car part made of a metallic plate having an embossed reenforcement 105 formed therein comprising a central portion, a longer portion on each side of said central portion having their extremities separated therefrom and their middles joined thereto, attaching pieces secured within said central portion with one side flush with the side of the plate from which the reenforcement protrudes, and lining boards secured to said attaching pieces extending perpendicularly thereto and bearing upon said attaching 110 pieces and upon the plate between the central portion and the other portions.

9. In a railway car, the combination of a frame member, a metallic plate having an embossed reenforcement formed therein, 120 comprising a central portion, a longer portion on each side of said central portion having their extremities separated therefrom and their middles joined thereto, said longer portion overlapping said frame member, and means for attaching said plate to said frame member positioned between the extremities of the longer portions.

10. In a railway car, the combination of a frame member, a metallic plate having an 125

embossed reinforcement formed therein, terminating within the opposite edges of the plate, comprising a central portion, and a longer portion on each side of said central portion having their extremities separated therefrom and their middles joined thereto, said longer portion overlapping said frame member, and means for attaching said plate to said frame member positioned between the extremities of the longer portions and aligned with said central portions.

11. In a railway car, the combination of a frame member, a metallic plate having an embossed reinforcement formed therein, comprising a central portion, and a longer portion on each side of said central portion

having their extremities separated therefrom and their middles joined thereto, said longer portion overlapping said frame member, and means for attaching said plate to said frame member positioned between the extremities 20 of the longer portions and aligned with said central portions.

12. In a railway car part made of a metallic plate having an embossed reinforcement formed therein comprising a central portion, 25 and a shorter portion on each side of said central portion having their extremities diverging and separated therefrom and their middles joined thereto.

VINTON E. SISSON.
